ELECTRIC SNAP SWITCH

John Weber and Nicholas J. Walsh, Schenectady,
N. Y., assignors to Alpine Electric Corporation,
Schenectady, N. Y., a corporation of New
York

Application April 10, 1935, Serial No. 15,700

10 Claims. (Cl. 200—64)

The present invention relates to electric switches and contemplates a design which may be embodied compactly and assembled readily. The invention particularly relates to switches of the rotary type wherein oscillating actuating elements are provided, the oscillating elements being moved manually in one direction and by torsion springs in the other direction. An important object of the invention is to provide means whereby the springs may be wound subsequent to assembly of the switches.

We have shown two embodiments of the invention in the accompanying drawings in which:

Figure 1 is a perspective view of an embodiment utilizing a pull chain as switch actuating means.

Figure 2 is a longitudinal section of the embodiment of Figure 1.

Figure 3 is an exploded view in perspective of the embodiment of Figure 1.

Figure 4 is a section substantially on line 4—4 of Figure 2.

Figure 5 is a perspective view of an embodiment utilizing a push button or plunger as switch actuating mechanism.

Figure 6 is a longitudinal section of the embodiment of Figure 5, and

Figure 7 is an exploded view in perspective of the embodiment of Figure 5.

Referring to the drawings and first to Figures 1 to 4, reference numeral 20 designates generally a box-like housing or casing preferably made up of two parts 21 and 22 which are riveted or bolted together and define between them a closed switch chamber. One side wall of the casing is constituted by the wall 23 of part 21 and the opposite side wall by the wall 24 of part 22, these two side walls being parallel, as here shown, and the casing parts abutting in a plane between these walls. The housing parts are of insulating material, such as a phenolic condensation product.

Portion 21 is formed with rectangularly arranged end flanges 25, 26 and side flanges 27, 28, portion 22 having flanges 29, 30 and 31, 32 registering with the former when the two parts are brought together. Diagonally opposite corner portions of the housing are thickened and provided with apertures through which the rivets 33 and 33a are passed to secure the parts together.

End walls 26 and 30 are provided with registering semi-circular recesses 26a and 30a which receive an externally threaded collar 34. At its inner end the collar is reduced to form a shoulder 55 on which is received an apertured square plate 35,

the extremity 36 of the collar being spun over the plate to secure the two together. Plate 35 is received in recesses 37 and 38 provided in parts 21 and 22, respectively, so as to hold the collar against axial movement, a thin nut 39 being screwed on the externally projecting portion of the collar. A finishing nut 40 is screwed on the outer extremity of collar 34 and through the collar and nut 40 is passed a pull chain 41. With nut 40 removed, collar 34 may be passed through an aperture in a supporting plate, strip, canopy or fixture and then nut 40 applied so that the plate is clamped between it and nut 39 to support the housing in desired position. Nut 40 has an internal shoulder which limits the extent to which it may be threaded on collar 34. If the supporting member is unusually thin, nut 39 may be screwed outwardly so that clamping action may be effected.

Adjacent the right hand corner opposite collar 34, Figure 3, portion 21 is provided with an inwardly extending boss 42 which has a cylindrical recess 43. Surrounding the boss are diametrically opposite inclined surfaces 44, 45 and 46, 47. Immediately inwardly of collar 34, part 21 is formed with a ledge 48 pierced at 49 and 50, the two openings being inwardly constricted by means of annular ribs 51 and 52.

Contact strips 53 and 54 have shank portions formed with collets 53a and 54a which are passed into openings 49 and 50 and turned under ribs 51 and 52 to hold the contacts in position.

Hollow rivets could of course be used in place of the integral collets. Conductors 55 and 56 have their bare ends passed through the collets and secured by drops of solder 57, 58. At their other ends strips 53 and 54 have segments 59 and 60 overlying the inclined surfaces 46 and 47 and lying flatly thereon. Surfaces 44 and 45 are exposed.

Directly opposite recess 43 portion 22 is provided with a similar recess 61 and formed on the inner surface of wall 24 in concentric relation to recess 61 is a full circular series of inclined teeth 62. Inwardly of this series of teeth wall 24 has formed therein an arcuate slot 63. A post 64 has its ends engaged in recesses 43 and 61 so as to extend directly between walls 23 and 24 in perpendicular relation thereto. Inasmuch as recesses 43 and 61 are blind, the post is held against axial movement. A preferably flexible insulating plate 65 overlies the contact strips and closely follows the chamber contours so as to be positioned thereby against edgewise movement. Plate 65 is provided with a circular opening 66.

concentric with post 64 and with a recess 67 which fits over a formation 67a on ledge 48, this formation serving as a chain guide. Opposite ledge 48 wall 23 has formed thereon a ledge 5 68, Figure 2, which underlies an edge of plate 65 and serves as a stop therefor.

A rotary switch element 69 of metal, mounted on post 64, has offset diametrically opposite contact portions 70 and 71 which simultaneously lie 10 either on fixed contacts 59 and 60 or on the inclined insulating surfaces 44 and 45. Member 69 has radially projecting lugs 72 spaced at 90° intervals. Mounted on post 64 directly adjacent member 69 is a disc 73 which has four tongues 15 74 offset toward member 69 and adapted to engage lugs 72 in one direction of movement of the disc. Disc 73 has a collar 75 providing an elongated bearing on post 64 and adjacent the collar is a tongue 76 struck from the opposite side of the 20 disc from tongues 74. Further, disc 73 has two diametrically opposite projecting tongues 77.

A washer 78 of insulating material has an eccentric opening 79 in one end of which is received collar 75, the collar being spaced from the edges 25 of the opening. Tongue 76 is disposed in the opposite end of the opening and the washer is rigidly secured to disc 73 by means of the tongues 77 which are bent into a notch 80 and a slot 81 in the washer and turned over the latter. One 30 end of the washer is shaped as an arm 82 provided on one side with a notch 83 which is engaged in one end of a loop 84, the other bent end of the loop having engaged therein the inner extremity of chain 41. Arm 82 normally extends toward 35 the upper left hand corner of the housing, Figures 1 and 3, its movement in a clockwise direction being limited by flange 25. A torsion spring 85 has at one end a hook 85a engaging tongue 76, the spring surrounding post 64 and collar 75 projecting into the adjacent end thereof. The other 40 end of spring 85 is radially extended as at 85b and is engaged by a tongue 86 struck from a disc 87, preferably of insulating material, which freely surrounds post 64 adjacent wall 24 and lies within 45 the circular series of teeth 62. The disc 87 is provided with peripheral notches 87a which through slot 63 may be engaged by a suitable implement, for example a pin, to rotate the disc. The extension 85b projects radially across teeth 50 62 and serves as a pawl for cooperation therewith, riding over them without the necessity for 55 any bodily displacement of disc 87.

The described parts may be conveniently assembled substantially in the order shown in Figure 3, spring 85 being positionable without initial tension. After assembly disc 87 may be rotated as above described, the disc carrying extension 85b with it and thus tensioning the spring to the desired degree, the extension locking with one 60 of teeth 62 to retain the spring adjustment. Spring 85, it will be understood is a compression spring as well as a torsion spring and serves to urge the rotary switch member 69 toward wall 23, disc 73 toward the switch member, spring end 65 85b into engagement with a tooth 62, and disc 87 against wall 24.

It will be understood that when chain 41 is pulled a 90° movement is given to disc 73 and through tongues 74 to the rotary switch element 70 69, spring 85 returning disc 73 relative to member 69 when the chain is released. Conductors 55 and 56 are connected when contact portions 70 and 71 bridge the fixed segments 59 and 60, the circuit being broken when portions 70 and 71 75 are on surfaces 44 and 45. Disc 73 is an oscil-

latory ratchet member for imparting rotary motion to member 69. Movement of disc 73 in a counterclockwise direction is limited by abutment of the expanded portion 87a of washer 78 with flange 28, the disc having an oscillating 5 angle of 90° plus.

An important feature of the invention is the provision of the full circular series of teeth 62 so that disc 87b has an unlimited range of adjustment, thus enabling spring 85 to be tensioned 10 adequately after assembly. Furthermore, the described arrangement is extremely compact and provides a completely enclosed switch chamber. The housing parts have no undercut surfaces and thus may be readily die cast, although the invention is not limited in this respect. Furthermore, while the housing preferably has the rectangular shape shown, this may be varied if desired. 15

In the embodiment just described it will be evident 20 that a torsion spring which must be wound in a clockwise direction can only be used in view of the fact that teeth 62 are operative as abutments only in one direction. In the embodiment of the spring holding means shown in Figures 5 25 to 7, either a dextrorse or a sinistrorse spring may be used, since the spring holding means is operative with either type. In exemplification of this principle I have shown herein an assembly substantially the same as that heretofore described, but provided with a push button or plunger instead of a pull chain. When the plunger is pushed the spring is tensioned and actuates the switch when the plunger is released. This being 30 the case, it is evident that the torsion spring must be wound in the opposite direction from that in the first embodiment.

Referring to Figures 5 to 7, reference numeral 20' designates a housing in general the same as that of Figure 1 and comprising the two parts 40 21' and 22'. The collar 34' is interiorly slightly different from the collar 34 of the first embodiment, having a relatively large inner cylindrical cavity 90 constricted at its outer end by an annular flange 91. A plunger 92 has a main portion 45 freely slidable in the constricted portion of the collar and an enlarged butt 93 slidable in the portion 90 of the collar, outward movement of the plunger being limited through abutment of the butt 93 with the flange 91. At its inner 50 end the plunger is provided with a conical recess 94. In as much as the butt may pass inwardly beyond the end of the collar to some extent, the ledge 48' of part 21', Figure 7, is grooved as 55 at 95 to provide clearance.

The fixed contacts 53 and 54 are exactly the same as those heretofore described, as are also the rotary switch member 69 and the ratchet disc 73. The insulating plate 65 may be omitted since its principal purpose in the first embodiment is to prevent the flexible pull chain from causing a short. The washer 78' has an arm 82' provided with an aperture 96, instead of the notch shown in Figure 3, and has engaged therein the bent end of a link 97 whose other 60 end rests in recess 94, Figure 6.

Spring 85' is wound in the opposite direction from spring 85. Its extremity 85a' adjacent disc 73 is carried out straight and instead of being hooked under tongue 76 merely abuts the inner 70 wall of the washer aperture 79'. The opposite end 85b' of the spring is radially extended and is gripped by a tongue 86' of notched disc 87'.

An annular rib 98 surrounds the bearing recess 61' on wall 24' of part 22' in concentric relation 75

to the recess. At intervals the rib is provided with threaded holes 99 which pass through wall 24' and in any of these holes may be threaded a screw 100 which is inserted from the front of wall 24' and whose inner end is adapted to be projected inwardly of rib 98. Within rib 98 wall 24' is provided with an arcuate slot 63'.

After assembling the parts, disc 87' is engaged through opening 63' and rotated in a counter-clockwise direction to tension spring 85', screw 100 during this operation being screwed outwardly so that its inner end is flush with flange 98 or it is removed entirely. When the proper adjustment of spring 85' has been made, screw 100 is threaded inwardly in a hole 99 just behind end 85b' of spring 85' so that the spring is held against unwinding. Washer 78' and disc 73 are thus urged in a counter-clockwise direction, being limited by the link 97 which is just to the left, Figure 7, of a straight line position with plunger 92. When the plunger is pressed inwardly, ratchet disc 73 is rotated in a clockwise direction relative to rotary element 69 through an angle slightly greater than 90° and when the plunger is released spring 85' returns the parts, disc 73 carrying element 69 with it to the new position. Movement of the disc 73 in a clockwise direction is limited through abutment of arm 82' of washer 78' with the inner face of flange 25'. The adjusting range of disc 87' is unlimited.

The discs 87 and 87', it will be noted, are rotatable in their planes of rest, i. e., are not bodily displaced from a rest position to a rotating position. This is advantageous in that since the spring is not compressed during adjustment by a preliminary bodily movement of the disc, its proper adjustment is more easily judged.

40 The slots 63 and 63' are confined within relatively small angles and thus do not weaken the housing walls materially and, furthermore, provide only limited areas through which dust and dirt might enter the casings. These areas, 45 moreover, are closed by the discs 87 and 87' with the exception of the small openings presented by the notches. The slots need have a length only sufficient to expose two adjacent disc notches. It is also possible to predetermine approximately the position of the spring ends 85b and 85b' so that they will not lie across the slots in the adjusting position of the springs and are thus fully protected. If the spring end should come across the slot, the disc may be reversely 50 rotated relative thereto so as to bring a full disc portion thereover.

Variations in detail and arrangement from what has been described are, of course, possible without departure from the invention and accordingly we do not limit ourselves except as in the following claims.

We claim:

1. Apparatus of the class described comprising a housing having opposite walls, a post extending between said walls, switch mechanism including a rotary element coaxial with said post, ratchet mechanism for driving said rotary element and including an oscillatory member oscillable about said post, manual means for moving said oscillatory member in one direction and a torsion spring surrounding said post and connected at one end to said oscillatory member for moving the latter in the other direction, a rotatable disc on said post between the other 55 end of said spring and one of said walls and

engaging the adjacent end of said spring, said one of said walls having a slot through which said disc is engageable to be rotated, said disc being rotatable substantially in its plane of rest throughout an unlimited range to tension said 60 spring, and means for holding the spring in any adjusted position.

2. Apparatus of the class described comprising a housing having opposite walls, a post extending between said walls, switch mechanism including a rotary element coaxial with said post, ratchet mechanism for driving said rotary element and including an oscillatory member oscillable about said post, manual means for moving said oscillatory member in one direction and a torsion spring surrounding said post and connected at one end to said oscillatory member for moving the latter in the other direction, a rotatable disc on said post between the other end of said spring and one of said walls, the end of said spring adjacent said disc being extended radially of the disc to project beyond the latter, means connecting the disc and said spring end so that upon rotation of the disc the spring is tensioned, said one of said walls having a slot through which said disc is engageable to be rotated, and means carried by said one of said walls for engaging said spring end whereby to hold the spring in tension.

3. An electric switch comprising an oscillatory member, manual means for moving said member in one direction and a torsion spring connected at one end to said member for moving the same in the other direction, a disc overlying and engaged with the other end of said spring, means on the opposite side of the disc from the spring and against which the disc constantly bears, the disc being rotatable through any desired range to tension the spring, and means for retaining the spring in any adjusted position, said last-named means comprising a full circular series of teeth cooperable with the end of the spring adjacent said disc.

4. An electric switch comprising an oscillatory member, manual means for moving said member in one direction and a torsion spring connected at one end to said member for moving the same in the other direction, a disc overlying and engaged with the other end of said spring, means on the opposite side of the disc from the spring and against which the disc constantly bears, the disc being rotatable through any desired range to tension the spring, and means for retaining the spring in any adjusted position, said last-named means comprising a movable abutment projectable into engagement with the end of the spring adjacent said disc.

5. An electric switch comprising an oscillatory member, manual means for moving said member in one direction and a torsion spring connected at one end to said member for moving the same in the other direction, a disc overlying and engaged with the other end of said spring, means on the opposite side of the disc from the spring and against which the disc constantly bears, the disc being rotatable through any desired range to tension the spring, and means for retaining the spring in any adjusted position, said last-named means comprising an abutment disposable in various positions about said disc to engage and hold the end of the spring adjacent said disc.

6. Apparatus of the class described comprising a housing, having opposite walls, a post extending between said walls, switch mechanism including a rotary element coaxial with said post,

ratchet mechanism for driving said rotary element and including a member oscillatory about said post, manual means for moving said oscillatory member in one direction and a torsion spring 5 surrounding said post and connected at one end to said oscillatory member for moving the latter in the other direction, a full circular series of teeth on the inner side of one of said walls concentric with said post, a rotatable disc on said 10 post between the other end of said spring and said toothed wall and engaging the adjacent end of said spring, said toothed wall having a slot therein through which said disc may be engaged to be rotated, and means projecting from said 15 disc and engageable with said teeth to hold the spring in adjusted position, rotation of the disc serving to tension said spring.

7. Apparatus of the class described comprising a housing having walls, a post extending between 20 said walls, switch mechanism including a rotary element coaxial with said post, ratchet mechanism for driving said rotary element and including an oscillatory member oscillable about said post, manual means for moving said oscillatory 25 member in one direction and a torsion spring surrounding said post and connected at one end to said oscillatory member for moving the latter in the other direction, a series of holes in one of said walls arranged on a circle concentric with 30 the axis of said post, a rotatable disc on said post between the other end of said spring and said one of said walls and engaging the adjacent end of said spring, said one of said walls having a slot therein through which said disc may be engaged 35 to be rotated whereby to tension said spring, and an abutment selectively disposable in said holes to engage the adjacent end of said spring to hold the latter in adjusted position.

8. An electric switch comprising a housing, an 40 oscillatory switch member within the housing, manual means for moving said member in one direction and a torsion spring connected at one end to said member for moving the same in the other direction, a disc overlying and engaged 45 with the other end of said spring, the casing having a wall on the opposite side of the disc from

the spring and against which the disc constantly bears, the disc having peripheral notches and said wall having an arcuate slot through which the disc notches are engageable to rotate the disc through any desired range to tension the spring, 5 the disc covering said slot with the exception of the exposed notches, and means for retaining the spring in any adjusted position.

9. An electric switch comprising a housing, an oscillatory switch member within the housing, 10 manual means for moving said member in one direction and a torsion spring connected at one end to said member for moving the same in the other direction, a disc overlying and engaged with the other end of said spring, the casing having a wall on the opposite side of the disc from the spring and against which the disc constantly 15 bears, the disc having peripheral notches and said wall having an arcuate slot through which the disc notches are engageable to rotate the disc 20 through any desired range to tension the spring, the disc covering said slot with the exception of the exposed notches, the slot being of a length to expose only two adjacent disc notches, and means for retaining the spring in any adjusted position. 25

10. An electric switch comprising a housing, an oscillatory switch member within the housing, manual means for moving said member in one direction and a torsion spring connected at one end to said member for moving the same in the 30 other direction, a disc overlying and engaged with the other end of said spring, the casing having a wall on the opposite side of the disc from the spring and against which the disc constantly bears, the disc having peripheral notches and 35 said wall having an arcuate slot through which the disc notches are engageable to rotate the disc through any desired range to tension the spring, the disc covering said slot with the exception of the exposed notches, and means for retaining the 40 spring in any adjusted position, said last-named means comprising a series of teeth on the casing wall adjacent said disc and cooperable with the end of the spring adjacent said disc.

JOHN WEBER.

NICHOLAS J. WALSH.

45
